US0D1053889S

(12) **United States Design Patent** (10) Patent No.: **US D1,053,889 S**
(45) Date of Patent: ** Dec. 10, 2024

(54) **DISPLAY SCREEN WITH A GRAPHICAL USER INTERFACE**

(71) Applicant: **Integra LifeSciences Corporation**, Princeton, NJ (US)

(72) Inventors: **LuAnn Grover**, Westerville, OH (US); **Jeffrey L. Jensen**, Phoenix, AZ (US)

(73) Assignee: **Integra LifeSciences Corporation**, Princeton, NJ (US)

(**) Term: **15 Years**

(21) Appl. No.: **29/845,272**

(22) Filed: **Jul. 6, 2022**

(51) LOC (14) Cl. **14-04**

(52) U.S. Cl.

USPC **D14/485**

(57) **CLAIM**

The ornamental design for a display screen with a graphical user interface, as shown and described.

DESCRIPTION

FIG. 1 is a front view of a display screen with a graphical user interface, showing an image of a first embodiment thereof; and,

FIG. 2 is a front view of an image of a second embodiment thereof.

The outermost broken line in each of the figures illustrates a display screen or portion thereof and forms no part of the claimed design. The remaining broken lines, illustrating portions of the graphical user interface, form no part of the claimed design.

1 Claim, 2 Drawing Sheets
